CLAIM

The ornamental design for a digital audio disc player, as shown and described.

DESCRIPTION

FIG. 1 is a perspective view of the front, right and top plan of a digital audio disc player showing our new design.

FIG. 2 is a front view of the design according to the invention.

FIG. 3 is a rear view of the design according to the invention.

FIG. 4 is a left side view of the design according to the invention.

FIG. 5 is a right side view of the design according to the invention.

FIG. 6 is a top plan view of the design according to the invention; and,

FIG. 7 is a bottom view of the design according to the invention.
